WINDOW LOCK

Andrew Fedor, Jr., Fairfield, Conn.

Application November 1, 1937, Serial No. 172,277

1 Claim. (Cl. 292—335)

The invention relates to a window lock and more especially to an automatic latching window lock.

The primary object of the invention is the provision of a lock of this character, wherein on the closing of the sashes of a window the lock automatically is actuated so as to latch the sashes in closed position, thus avoiding the necessity of hand latching or locking of such sashes.

Another object of the invention is the provision of a lock of this character, wherein the liability of the window sashes being unlocked when closed is avoided in that such sashes on the closing thereof will be latched automatically in their closed position, only requiring hand release for the opening thereof.

A further object of the invention is the provision of a lock of this character, wherein the construction of the same is novel in its entirety and is automatic in the working thereof for the latching of window sashes closed.

A further object of the invention is the provision of a lock of this character, which is simple in construction, readily and easily applied to the meeting rails of window sashes, thoroughly reliable and efficient in operation, automatically acting, strong, durable, and inexpensive to manufacture and install.

With these and other objects in view, the invention consists in the features of construction, combination and arrangement of parts as will be hereinafter more fully described, and illustrated in accompanying drawing, which discloses the preferred embodiment of the invention and pointed out in the claim hereunto appended.

In the accompanying drawing:

Figure 1 is a fragmentary vertical sectional view through a window showing the sashes in separated or partly opened relation to each other and the lock constructed in accordance with the invention applied.

Figure 2 is a view similar to Figure 1 showing the lock in position for locking the sashes closed.

Figure 3 is a sectional view on the line 3—3 of Figure 1 looking in the direction of the arrows.

Figure 4 is a sectional view on the line 4—4 of Figure 1 looking in the direction of the arrows.

Similar reference characters indicate corresponding parts throughout the several views in the drawing.

Referring to the drawing in detail, A designates generally a portion of a window frame in which are slidably fitted upper and lower sashes, portions of these being indicated at B and C, respectively, and are of standard make.

Associated with the sashes of the window slidably fitted in the frame A is an automatic window lock constituting the present invention and comprises a bolt housing or casing 5 preferably made from metal in which is slidably fitted a locking bolt 6 of the spring projected type. This housing 5 is securely fastened to the meeting rail of the lower sash while fastened to the meeting rail of the upper sash is a keeper 7 for alignment with the housing 5 on the closing of the sashes within 10 the window frame A and such keeper 7 accommodates the latching end of a spring projected bolt 6. The bolt 6 has attached thereto a pull handle 8 working through a clearance in the housing 5 and such bolt is held under tension by 15 a coiled spring 9 about the pull handle 8 so that the bolt is urged into locking position.

Pivoted interiorly of the housing 5 on one side wall thereof is a rocking arm or lever 10 having the notched end 11 engageable with a stop 12 20 formed on and projecting laterally from the bolt 6 and this lever when engaging the stop 12 holds the bolt retracted in the housing 5 or in unlocking position.

Pivoted within the keeper 7 is an adjustable striker 13 being pivoted at 14 to one side wall of said keeper 7 and such striker 13 is adjustable under the action of an eccentric or cam 15 operated from a turning screw or arbor 16 accessible without the keeper 7 while pivoted 30 within the housing 5 is a cam faced trigger 17 adapted for engagement with the striker 13 when brought into the path of the latter, the pivot for the trigger 17 being indicated at 18. Pivoted to the arm or lever 10 at the end overhanging the 35 trigger 17 is a trip 19, being swingable only in a counter-clockwise direction for riding the trigger 17 and in this way the arm or lever 10 at the latching end 11 can be unlatched from the stop 12 to free the bolt 6 for the engagement thereof in 40 the keeper 7 on the closing of the sashes B and C within the window frame A. The bolt 6 when retracted within the housing 5 is latched in this position by the arm 10 at the end 11 engaging the stop 12. The trigger 17 is acted upon by a 45 spring 20 urging it into the path of the striker 13 and similarly the arm or lever 10 is acted upon by a spring 21 urging it into latching position to have the end 11 in the path of the stop 12 on the bolt 6. When the trigger 17 is actuated by contact with the striker 13, the trip 19 rides the trigger at the working or cam face 22 thereof for the automatic release of the bolt 6 to allow the same to be thrown to locking position for engaging the keeper 7.

On adjustment of the striker 13, it can be projected from the keeper 7 the desired degree for the proper action of the trigger 17. The trip 19 is held against clockwise movement or limited in this direction of movement by an abutment 23 on the lever 10 in the path of said trip, so that the trigger 17 on swinging in one direction through its cam face will rock the arm or lever 10 for disengaging the stop 12 and thus freeing the bolt 6 to be projected by the spring 9 acting therewith.

From Figures 1 and 2 of the drawing, it should be apparent that when either the upper or lower sash is in an open position and closed, the lock automatically operates for the latching of both sashes in closed position within the window frame A. When it is desired to release either sash, the bolt 6 is retracted in the housing 5 of the lock, this being accomplished by pulling upon the pull

knob 8 hereinbefore set forth and the arm or lever 10 latches the bolt in its retracted position.

What is claimed is:

A window lock comprising a bolt casing, a spring-projected bolt within said casing, a lug on said bolt and projecting laterally therefrom, a rocking lever pivoted in the casing between one side thereof and said bolt for disposition in the path of the lug, a trigger mounted for vertical swinging movement within the casing for engagement with a striker, a trip on the lever and swingable counterclockwise for riding engagement with the said trigger, a cam formed on the trigger and coacting with the trip for effecting the rocking of the lever and disengagement thereof from the lug, and springs acting upon the trigger and the said lever for urging the same in one direction.
